UNITED STATES PATENT OFFICE.

WILLIAM SENIOR, OF MANCHESTER, ENGLAND, ASSSIGNOR TO GEORGE ALEXANDER KENNEDY, OF SAME PLACE.

DIFFERENTIAL GEARING.

SPECIFICATION forming part of Letters Patent No. 642,495, dated January 30, 1900.

Application filed July 12, 1898. Serial No. 685,793. (No model.)

To all whom it may concern:

Be it known that I, WILLIAM SENIOR, a subject of the Queen of Great Britain, residing at Pendleton, Manchester, in the county of Lancaster, England, have invented a new and useful Improved Differential Gearing, of which the following is a specification thereof.

This invention relates to that kind of apparatus for grinding the cards of carding-engines known as the "Horsfall" grinder, the object being to apply thereto a simple and noiseless differential motion for driving the screw from the tube.

The invention consists in the employment of an intermediate worm for actuating the screw from the tube, as hereinafter described.

The invention will be readily understood from the following description on reference to the drawings hereunto annexed.

Figure 1 is an elevation, partly in section; and Fig. 2 is a section through A A on Fig. 1. Fig. 3 is a sectional elevation of the casing a, and Fig. 3^a a front view of the bracket a^x thereof. Figs. 4 and 4^a show, detached, the parts carried by the tube. Figs. 5 and 6 show, detached, the worm-wheel on the screw. Figs. 7 and 8 illustrate two modifications, Fig. 7^a being a detached face view of the worm-wheel used on that shown in side elevation at Fig. 7. Fig. 8^a represents a sectional plan of Fig. 8, drawn to a smaller scale. Fig. 9 is a front view, partly in section and partly cut away, of so much of a Horsfall grinder as is necessary to show the application of this invention. Fig. 10 is a plan of the right-hand end of Fig. 9.

Referring to Fig. 9, e represents the grinder-wheel of the grinder, adapted to be fixed to a carding-engine, b the tube, and d the screw.

According to my invention I prefer to provide a circular casing a to be placed on the end of the grinder and a suitable bracket a^x to prevent it from revolving when fixed on the frame, as usual. The bracket a^x,

Figs. 9 and 10, rests in the slot in the usual slotted or forked bracket x (fixed to the carding-engine) when the apparatus is dropped into these bearings or brackets x to grind the card-teeth. Upon the end of the tube b

50 which projects part way into the casing a I fix a suitable bracket b' or its equivalent,

carrying bearings b², supporting a short shaft c, on which is fitted a worm c', which is rotated as the tube b revolves by a suitable beveled worm-wheel c² in gear with an internal spiral thread a², formed or fitted inside the cylindrical part of the fixed casing a of the apparatus. The worm c', thus rotated by this beveled worm-wheel, is in gear with a worm-wheel d' on the screw d, which it thus drives at the desired speed.

The described differential gearing, besides being simple and compact, is almost noiseless in action, and thus the setting of the grinder is greatly facilitated.

In some cases the fixed spiral thread may be formed on the inner face of one end of the casing, and in that event the form of the worm-wheel will be changed. Such modification is represented in Figs. 7 and 7^a, where a¹² represents the fixed spiral thread on the end of the casing a¹⁰, and c¹² is the modified form of worm-wheel on the same shaft with the worm c', which revolves in the bearings b² and gears with the worm-wheel d', as before described.

Another modification is illustrated in Figs. 8 and 8^a. In such case the shaft c¹⁰ and worm c¹¹ turn in bearings c³, forming part of the casing a²⁰, which is held from turning by a suitable bracket a⁴, as before. The worm c¹¹ is driven by a worm-wheel b³ on the tube b and in turn drives a worm-wheel d¹¹ on the screw d, which worm-wheel d¹¹ has a fewer number of teeth than the worm-wheel b³ to produce the differential motion, as before described. The pitches of the worm-wheels d¹¹ and b³ must be such as to allow of an angular or wedging action both for driving-wheel and for driven wheel. The greater this angle is the more certain the worm-wheel b³ is to turn the worm; but so that the worm may in turning rotate the wheel d¹¹ it is made about forty-five degrees.

I claim as my invention—

1. The combination of a Horsfall grinder having a screw and a tube, with a casing placed on the grinder and provided with a worm suitably driven from the tube, and a worm-wheel in said casing fixed on the screw and adapted to be driven by the said worm, substantially as described.

2. The combination of a Horsfall grinder having a screw and a tube, with a casing placed on the grinder and provided with a fixed worm, a worm-wheel in said casing fixed on the screw, brackets fixed on the tube within the casing and carrying a worm adapted to drive the said worm-wheel on the screw, and a wheel adapted to be driven by the fixed worm and to drive the worm carried by the brackets, substantially as described.
3. The combination of a Horsfall grinder having a screw and a tube, the said screw

and tube each being provided with a worm-wheel, and a worm carried in fixed brackets, 15 adapted to be driven by the worm-wheel on the tube and to drive the worm-wheel on the screw, substantially as described.

In testimony whereof I have signed my name to this specification in the presence of 20 two subscribing witnesses.

WILLIAM SENIOR.
